By Att. Anthony Maina attg.

UNITED STATES PATENT OFFICE.

CARL D. BRADLEY, OF ROGERS CITY, MICHIGAN.

METHOD OF BUILDING BREAKWATERS.

Application filed December 29, 1924. Serial No. 758,624.

To all whom it may concern:

Be it known that I, CARL D. BRADLEY, a citizen of the United States, residing at Rogers City, in the county of Presque Isle and State of Michigan, have invented certain new and useful Improvements in Methods of Building Breakwaters, of which the following is a specification.

This invention relates to a new and improved method of building breakwaters or the like and more particularly to a method of building such structures by substantially continuous deposition of material.

Breakwaters of the rubble type have heretofore been generally constructed by the dumping of material from scows in small quantities at a time. This method of procedure is expensive and takes considerable time, since the scow must be carefully placed in the exact position for the deposition of each small lot of material. This method also requires a large number of handlings of the material, which must be loaded into the scow from stock piles or other source of supply.

It is an object of the present invention to provide a new and improved method for constructing breakwaters or similar structures, and more particularly constructing breakwaters of the rubble mound type, or of the caisson type having a rubble mound foundation by the substantially continuous deposition of the material.

It is a further object to provide a method of this character whereby the material may be directly deposited from a steamer into position in the breakwater docks or other structure.

It is also an object to provide a method whereby the material may be deposited in mounds extending continuously along the line of the structure and whereby by depositing a plurality of mounds, a structure of relatively large dimensions may be brought to approximately final form.

Other and further objects will appear as the description proceeds.

I have illustrated in the accompanying drawings somewhat diagrammatically, means and method for carrying out the invention, and the breakwater formed, at various stages of construction.

In the drawings:

Figure 1 is a plan view showing a steamer engaged in constructing a foundation for a caisson breakwater according to this method;

Figure 2 is a view similar to Figure 1, but on a smaller scale and showing the means for maneuvering the steamer;

Figure 3 is a section of a partly completed breakwater taken on line 3—3 of Figure 1;

Figure 4 is a view similar to Figure 3, but taken on line 4—4 of Figure 1;

Figure 5 is a view similar to Figure 3, but taken on line 5—5 of Figure 1;

Figure 6 is a view similar to Figure 3, but taken on line 6—6 of Figure 1;

Figure 7 is a cross section of the completed breakwater;

Figure 8 is an elevational view partly in section, showing a steamer adapted for carrying out this method; and

Figure 9 is a cross section of the steamer, showing the unloading boom swung out laterally.

The present method is best carried out by means of steamers of the self-unloading type, such as shown diagrammatically in Figures 8 and 9. These steamers comprise a plurality of hoppers 11, each of which is provided with a hopper gate 12 adapted to permit discharge of material from the hoppers onto the conveyor 13. It will be understood that the hoppers are normally loaded through the hatches 14.

Material deposited on the conveyor 13 is carried and dumped from the end of the conveyor into the hopper 14 from which it is carried by the bucket elevator 15. From the elevator, it is dumped onto the conveyor 16 carried by the discharging boom 17. As best shown in Figure 9, this boom 17 may be swung out well to the side of the ship and the material may be unloaded and deposited at a considerable distance from the side of the ship. The boom 17 is raised or lowered by means of cables 18 and may be swung laterally by means of cables 19 operated by winches 20, as shown in Figure 1.

The boom 17 carries upon its outer end the platform 21, which supports the winch 22, which handles the sounding cable 23, carrying the sounding lead 24.

In the formation of a breakwater or the like, using self-unloading vessels of this character, the vessel is stationed adjacent and preferably parallel to the location of the proposed breakwater. As shown in Figure 2, a series of pile clusters 25 may be driven into the bottom adjacent the proposed line. The ship 26 is brought up against these

piles and is moored by the cables 27, 28 and 29 to the anchored buoys 30, 31 and 32. The boom 17 is then swung out over the side of the ship and is aligned at the proper position 5 for depositing material, by means of range stakes or poles 33, 34 and 35.

In the caisson form of breakwater shown by way of illustration, the breadth of the lower rubble portion is comparatively great, 10 and the angle of repose of the material is approximately one and one-half to one. Consequently, a rather broad rubble base is necessary to support the concrete super-structure of the breakwater. This broad 15 base is formed by depositing three adjacent longitudinally extending piles of material.

For example, the boom 17 will be first 20 swung out until the series of posts 34 are brought in line by an observer on the plat- form at the end of the boom. The end of the 25 boom is located adjacent the material last deposited, or at the point at the beginning of the breakwater. The unloading con- 30veyor and elevators are put into operation, 25 the hoppers being opened at such times as to properly unload the vessel, and the mate- 35rial is unloaded into the water over the end of the belt 16 on the boom.

An operator on the platform 21 continu- 30ously operates the sounding line and when 35 the pile of material reaches the desired height, the cables 27, 28 and 29 are hauled in to move the vessel forward a short dis- 40tance and the deposition of material con- 45tinues at this spot until the desired height is reached. The movement of the vessel may be intermittent or may be continuous. This method of operation continues until the outer pile or portion 36, as shown in Figure 40 3, is deposited throughout the entire length of the breakwater or other structure or such portion thereof as desired.

It should be stated that during this depo- 45sition and movement any slight lateral movements of the vessel are taken care of by an observer on the platform keeping the poles 34 lined up by having the boom swung in or out, as necessary, by means of the 50 winches 20 and cables 19.

After the desired length of the outer pile 55 36 has been deposited, the vessel is brought back to the starting point and the same process is carried out, with the boom swung in closer to the vessel so that the pile 37 is deposited on the line of the poles 35. After 60 this pile has reached the desired length, the vessel is brought back and goes over the course the third time, depositing the pile intermediate to the piles 36 and 37 and lined up on the intermediate poles 33. This final 65 deposition, brings the intermediate portion 38 of the pile to the level of the outer portions 36 and 37 and approximately levels the pile, as shown in Figure 4.

The pile may be finally brought to more

perfect level by means of a scow 39, shown in Figure 2, carrying a pile of material and the steam shovel 40. This scow would be moved over the pile as shown in Figure 4, 70 and shovels full of rock deposited, as indicated necessary by soundings or by divers. Divers may follow the scow 39 and complete the leveling. In the form of breakwater shown by way of illustration, the top of the rubble pile is located well below the surface 75 of the water and concrete caissons 41 are placed on top of the pile, the caissons ex- 80tending above the water level.

The caissons are hollow and formed of concrete and are floated into position. They 80 are then pumped full of water to sink them when over the proper point. The water may be pumped out if necessary to readjust their position. When finally put in place the caissons are partly filled by means of 85 stone delivered from the boom. The upper portion is then filled with concrete as shown at 42 of Figure 7.

As a final step a protecting filling of 90 larger stones 43 is deposited along the face 95 of the caisson and rubble pile. These stones may run to quite larger sizes and may be deposited in any desired manner.

It will be understood that a large number of anchored buoys may be provided so that 95 the vessel may be carried along the line of the breakwater for a considerable distance.

The method has been described in connec- 100tion with a breakwater which must be lev- 105eled below the surface of the water. How- ever, it is obviously equally well adapted for use where the breakwater is entirely of the rubble mound construction. In this case, the material may be deposited until it shows above the water any desired distance. It is 105 also adapted to other structures than break- 110waters, such as cribs, docks and bulkheads, which require a similar deposit of material.

It will be understood that in some cases 110 it may all be deposited by a single move- 115ment of the vessel along the line; in others, two, three or more parallel piles may be de- 120posited as has been described. This method of breakwater construction entirely eliminates many handlings of the material inci- 125dient to present methods of construction, and decreases the cost and time required for breakwater construction. The material may be loaded onto steamers at or adjacent the quarries and carried directly to the location where it is to be deposited. It then may be deposited in place with but a single han- 130dling by the mechanical unloading means and at high speed.

This method has been very successfully 125 carried out with vessels of ten thousand tons burden, capable of discharging their cargo at a rate of more than two thousand tons per hour. Due to the length of the boom, 135 the material may be deposited at one hun-

dred and twenty five feet or more from the side of the vessel.

While one particular vessel capable of such use and one particular method has been described in detail, it is to be understood that I contemplate such changes and modifications as come within the spirit and scope of the appended claims.

I claim:

- 10 1. The method of constructing breakwaters or the like which comprises continuously depositing the breakwater forming material progressively along the longitudinal line of the breakwater, the point of deposit moving forward as the deposit reaches the desired height.
- 15 2. The method of constructing breakwaters or the like which comprises continuously depositing the breakwater forming material along the longitudinal line of the breakwater, testing the height of the deposited pile as the deposit progresses and moving the point of deposit along the line as the deposit reaches the desired height.
- 20 3. The method of constructing breakwaters or the like which comprises continuously unloading material from a movable source of supply and moving the source of supply and point of deposit along adjacent the line of the deposit as the deposit reaches the desired height.
- 25
- 30

4. The method of constructing breakwaters or the like which comprises continuously unloading material from a movable source of supply, continuously testing 35 the height of the deposit during the deposition of the material, and moving the source of supply and point of deposit along adjacent the line of the deposit as the deposit reaches the desired height.

40 5. The method of constructing breakwaters or the like which comprises continuously depositing material in adjacent piles extending longitudinally along the edge of the desired location, the piles taking 45 their form by gravity and depending upon the angle of repose of the material, and subsequently leveling the tops of the piles.

50 6. The method of constructing breakwaters or the like which comprises continuously depositing material in adjacent piles extending longitudinally along the edge of the desired location, the piles taking 55 their form by gravity and depending upon the angle of repose of the material, and subsequently depositing a third pile longitudinally extending between the first piles whereby the intermediate portion of the breakwater is approximately leveled.

Signed at Chicago, Illinois, this 26th day 60 of December, 1924.

CARL D. BRADLEY.
